SWITCH

Carl Wesschke, St. Paul, Minn.

Application April 15, 1937, Serial No. 137,661

11 Claims. (Cl. 266—116)

5 My invention relates to an improvement in switches of a type designed to maintain a contact through a certain period of movement of a movable member in one direction, and to break contact through a predetermined movement of the movable member in the opposite direction.

10 It is the object of my invention to provide a switch which is adaptable for use in the provision of a circuit making and breaking means, operable in recurrent cycles. This switch readily adapts itself for use in combination with a thermostatic element for actuation of a circuit breaking means. When thus arranged, my switch is operable for use for any device in which a circuit breaker 15 operable in recurrent cycles is desired. For example, my switch may be used to operate lighting circuits which should be closed only during a certain period of the day to open the circuit after a predetermined interval. My switch may also 20 be used for opening the circuit to any electrically operated device such as a refrigerator, in order to provide a defrosting period during which the circuit to the motor of the refrigerator is opened at intervals.

25 Many types of switches operable in recurrent cycles have been provided for accomplishing the same purpose or a similar purpose to that for which the present switch is designed. These former constructions, however, usually have necessitated the provision of a constantly operated motor which opens and closes a circuit at predetermined intervals. Thermostatic motors have been previously formed to accomplish the rotation of a rotatable member. These motors, however, have previously been relatively complicated 35 and have not been used for operation of a circuit breaker through an adjustable period of time.

30 It is a purpose of the present invention to provide a simple switch which is thermostatically operated and which simultaneously operates a rotatable member which in turn actuates a recurrently operable circuit breaker. By this means, a device for controlling a circuit may be 40 recurrently actuated by a device which is extremely simple and inexpensive to manufacture and which costs an extremely small amount to operate.

45 It is a purpose of my invention to provide a deflectable thermostatic element which operates a switch arm. This switch arm is normally slidably in contact with a suitable contact plate. Upon extreme deflection of the thermostatic element, however, the switch arm is moved out of 50 contact with the contact plate and is held out of

5 contact with this plate through a predetermined movement during which the thermostatic element is deflecting in the opposite direction. The means holding the switch arm out of contact with the contact plate also acts to hold the arm in contact with the plate as it deflects into extreme position, thus creating a snap action when the thermostatic element deflects sufficiently. The thermostatic element may act either by a normal rise and fall in temperature, or may be actuated by 10 a heating element connected in the circuit controlled by the switch arm. When arranged in this latter manner, the switch arm closes the circuit to the heating element throughout its deflection in one direction until the switch arm 15 is deflected beyond the means holding the switch arm in contact with the contact plate. In this point of the movement, the contact arm snaps out of contact with the plate and remains out of contact therewith during the return deflection of 20 the thermostatic element as this element cools. Upon reaching a certain point in the return deflection, the switch arm again snaps into engagement with the contact plate again closing the circuit to the heating element, whereupon the 25 foregoing cycle is repeated.

It is a feature of my invention to provide a 30 rotary element used in conjunction with the switch arm and operated thereby during the return deflection of the thermostatic element. It is obvious that the means holding the switch arm 35 out of contact with the contact plate may also be used to hold the switch arm in cooperative relationship with the rotary member during the same period of time, thus acting to rotate the 35 rotatable member a predetermined distance during each actuation of the thermostatic element.

It is a further feature of my invention that the snap action switch which I provide may be 40 used in conjunction with any movable operating member in place of the thermostatic element and will act in a similar manner to maintain contact throughout a certain predetermined movement of the operating member, and to break contact at a predetermined point of the movement of the 45 operating member in each direction.

It is a further feature of my invention to provide a circuit breaking means operable by a rotating member to close a circuit during a predetermined distance of rotation, and to open the 50 circuit during the remaining portion of the rotation. In this device I incorporate a means of varying the time of contact so that the circuit may be broken throughout a longer or shorter period of time.

These and other objects and novel features of my invention will be more clearly and fully set forth in the following specification and claims.

In the drawing forming a part of my specification:

Figure 1 illustrates a top plan view of my switch with the cover removed therefrom.

Figure 2 illustrates the switch in a view similar to that of Figure 1, showing the parts in a different position.

Figure 3 is an elevation view of the switch and cover therefor, as it would appear along the line 3—3 of Figure 1.

Figure 4 is a perspective view of the thermo-static motor showing the operation thereof.

Figure 5 is a side elevation view of my switch with the cover removed.

Figure 6 is a perspective view of a slightly different form of switch embodying the snap action for opening and closing a circuit.

My switch A comprises a base 10, having mounted along one side thereof a block 11 of insulating material. The shape of this block 11 is perhaps best shown in Figure 5 of the drawing.

25 A slot 12 is cut into the block 11 near one end thereof and a strip of bimetallic material 13 is inserted in the slot 12. The bimetallic strip 13 is held in position by the bolt 14 extending through a portion of the block 11 from one end 30 thereof, and terminating in a notch 15 in the block 11.

A sleeve of insulating material 16, such as asbestos or the like, envelops a portion of the bimetallic strip 13, and a heating element 17 is wound about the sleeve 16. A spring arm 18 having a downwardly extending end 20, is secured at 21 to the free end of the strip 13. This downwardly extending end 20 slides over a block 22 of insulating material partially covered by a contact plate 23. An upwardly extending cam lug 24 of insulating material, projects upwardly from the block 22 adjacent the contact plate 23. The block 22 is secured to the base 10 of the switch A.

Upon deflection of the strip 13, the arm 18 is carried forwardly, the downwardly extending end 20 slidably contacting the contact plate 23. The path of movement of the end 20 is obstructed by the lug 24 so that continued deflection of the strip 13 causes the end 20 of the arm 18 to slide 45 along the plate 23 near the edge thereof, until the end 20 passes the lug 24. During this movement, the arm 18 is flexed out of normal position to some extent. Upon movement past the lug 24, however, the end 20 moves by force of the resiliency of the arm 18 snapping out of contact with the plate 23, and sliding over the surface of the block 22. As the strip 13 flexes from the position 50 illustrated in Figure 2 back to the position illustrated in Figure 1, the lug 24 prevents movement of the end 20 of the arm 18 back on to the contact plate 23 until the strip 13 flexes a predetermined amount. The movement of the end 20 of the arm 18 along the lug 24, flexes the arm 18 so that when the end 20 clears the lug 24, this end 55 20 will snap into contact with the plate 23. Thus in both directions of movement of the strip 13 a contact is provided with a snap action.

Rotatably mounted upon a spindle 25, I provide a gear 26 which also rotates a pinion 27. The gears 26 and 27 are prevented from rotating in one direction by the spring ratchet pawl 28. The pinion 27 engages the gear 29 which carries therewith a cam 30. The cam 30 and gear 29 are mounted upon a suitable spindle 31.

75 A spring arm 32 is secured in a slot in the

insulation block 11 and is provided with a turned down end 32' adapted to engage the cam 30. A supplementary spring leaf 33 provides additional spring tension without making the arm 32 excessively heavy. A bearing strip 34 is provided 5 near the end of the spring arm 32 to hold a portion of the arm 32 rigid.

A spring arm 35 and a supplementary spring arm 36 are slidably secured in a slot 37 in the insulation block 11. These spring arms 35 and 36 are secured to an operating push rod 38 having an operating button 40 of insulating material formed thereon. Vertical notches 41 are formed in the block 11 adjacent the slot 37, and the arms 35 and 36 are bulged outwardly to some extent to spring into these notches 41 when the arms 35 and 36 are in extreme positions. The free end of the arm 35 is provided with a bearing member 42 which engages the bearing strip 34 on the strip 32.

The cam 30 normally engages the bearing member 42 on the arm 35 which contacts the bearing strip 34 on the arm 32 to close the contact between the arms 32 and 35. During the rotation of the cam 30, however, the bearing end 42 drops away from a high point 43 of the cam 30. The end 32' of the arm 32, however, remains in contact with the high portion of the cam, thus acting to separate the arms 32 and 35, and to break contact therebetween. The contact between the arm 35 and the arm 32 remains broken until the end 32' of the arm 32 drops from the high point 43 of the cam 30 bringing the arms 35 and 32 into contact. By maintaining the arm 32 in a constant position, and by moving the arm 35 inwardly as shown in Figure 1 or outwardly as shown in Figure 2, the length of time between the dropping of the arm 35 from the high point of the cam 30 and the dropping of the end 32' from the high point 43 may be varied thus increasing or decreasing the period of time during which the circuit between the arms 32 and 35 is broken.

In operation the current to the switch A may be supplied through the wire 44 to the contact plate 45 23 and to the arm 35, and by the wire 45 to one end of the heating element 17. The other end of the heating element 17 is in contact with the bimetallic strip 13 which is electrically connected to the arm 18. The external circuit to 50 be broken is connected to the wire 46 which is connected to the supply wire 45 and the wire 47 which is electrically connected to the arm 32. When the current is supplied through the wires 44 and 45, a circuit is closed through the wire 44 to the contact plate 23, through the arm 18 and the heating element 17 to the other supply wire 45. The heating element provides heat which deflects the strip 13, moving the end 20 of the arm 18 along the contact plate 23 until it clears 55 the lug 24. The arm 20 then snaps over on to the insulating surface of the block 22 and the circuit to the heating element 17 is broken. The end 20 of the arm 18, however, simultaneously engages between two adjacent teeth of the gear 26, 60 and as the strip 13 returns from the deflected position in Figure 2 to the cold position of Figure 1, the gear 26 is rotated a short distance. Rotation of the gear 26 acts through the pinion 27 to rotate the gear 29 advancing the cam 30 slightly. 65 The end 20 of the arm 18 is held in engagement with the gear 26 until the end 20 clears the lug 24, whereupon the end 20 snaps back into contact with the plate 23 disengaging itself from the gear 26. As may be seen, the external circuit to be 70 75

controlled extends through the wire 44, the arms 35 and 32, and the wire 41, returning through the wire 46 to the other supply wire 45. Whether or not this external circuit is broken depends entirely upon the position of the arms 32 and 35 and the cam 38. The movement of the arm 18 is diagrammatically shown by small arrows in Figure 4 of the drawing.

In Figure 6 I illustrate a simple switch embodying my system of snap action. This switch is illustrated as having a longitudinally movable separating bar 49 extending through journals 50. Movement of the bar 49 is limited by stops 51. A flexible arm 52 is secured to the insulating bar 49 and is provided with a downwardly extending end 53 in slidable contact with the plate 54. The arm 52 slides along the plate 54 until it engages a lug 55 mounted adjacent the edge of the plate 54. The lug 55 is angularly disposed with respect to the movement of the arm 52, and acts to deflect the arm 52 to one side. This deflection of the arm 52 continues until the end 53 thereof clears the lug 55, whereupon the arm 52 snaps back behind the lug 55 on to the insulating block 56. A circuit between the arm 52 and the plate 54 is in this way broken. Upon return movement of the insulating arm 49, the arm 52 engages the back surface of the lug 55 and is deflected in the opposite direction to its previous deflection until moved sufficiently to clear the lug 55, whereupon this arm snaps into engagement with the contact plate 54, thus closing the circuit between this plate and the arm 52.

It may be seen that the application of a switch of this type is virtually unlimited, and that my construction may be applied to many different types of devices. With this construction, the use of relay is avoided, a snap action between the contacts providing a sufficiently good electrical connection to obviate the necessity thereof for most purposes.

In accordance with the patent statutes, I have described the principles of construction and operation of my switch and while I have endeavored to set forth the best embodiments thereof, I desire to have it understood that this is only illustrative of a means of carrying out my invention and that obvious changes may be made within the scope of the following claims without departing from the spirit of my invention.

I claim:

1. A thermostatic motor comprising a base, a rotatable member mounted thereon, a bimetal strip secured at one end to said base, means secured to the opposite end of said strip and movable by deflection of said strip in one direction into engagement with said rotatable member, and means engageable with said movable means for holding said movable means in contact with said rotatable member during a predetermined rotation of said rotatable member during deflection of said strip in the opposite direction.

2. A thermostatic motor comprising a base, a rotatable member mounted thereon, a bimetal strip secured at one end to said base, means secured to the other end of said strip and movable upon deflection of said strip into contact with said rotatable member, means guiding said movable means to delay contact of said movable means and rotatable means until the strip deflects a predetermined distance, said means holding said movable means in contact with said rotatable means throughout a predetermined return deflection of said strip.

3. A thermostatic motor comprising a base, a

rotatable member thereupon, a bimetal strip secured at one end to said base, resilient means secured to the other end of said strip and movable therewith by deflection thereof into contact with said rotatable member, means guiding said resilient means out of its normal path of movement and flexing said resilient means, said guiding means permitting said resilient means to snap into contact with said rotatable member when released from said guiding means, said guiding means flexing said resilient means in the opposite direction, holding said resilient means into engagement with said rotatable member for a predetermined distance and releasing said resilient means to snap said resilient means out into the normal path of movement of said resilient means.

4. A thermostatic motor comprising a base, a rotatable member mounted thereupon, a bimetal strip secured at one end on said base, a dog secured to the other end of said strip, means preventing rotation of said rotatable member in one direction, deflection of said strip moving said dog into engagement with said rotatable member to rotate the same.

5. A thermostatic motor comprising a base, a rotatable member thereupon, a means laterally deflectable by a rise in temperature secured at one end to said base, a means for preventing rotation of said rotatable member in one direction, lateral deflection of said deflectable means moving said deflectable means into engagement with said rotatable member to rotate said rotatable member.

6. A thermostatic motor comprising a base, a rotatable member mounted thereupon, a laterally deflectable member on said base deflected by a rise in temperature, a dog engageable with said rotatable member mounted on said deflectable member and operable to rotate said rotatable member, a contact plate, means on said dog slidable over said contact plate during the time said dog is out of contact with said rotatable member, a heating element adjacent said deflectable member, and a circuit extending through said contact plate, said dog, said heating element and a suitable source of current supply, to energize said element when said dog is out of engagement with said rotatable member.

7. A thermostatic motor comprising a base, a rotatable member mounted for rotation with respect thereto, a deflectable member deflectable by heat secured at one end to said base, means on the other end of said deflectable member engageable with said rotatable member to rotate the same upon deflection, contact means engageable with said engageable means during the time said engageable means is out of engagement with said rotatable means, a heating element adjacent said deflectable means, and a circuit through said engageable means, said contact means and said heating element closed when said engageable means is out of contact with said rotatable means.

8. A thermostatic motor comprising a base, a rotatable member mounted thereupon, a deflectable temperature responsive member secured at one end to said base, means secured to the free end of said deflectable member engageable with said rotatable member to rotate the same, insulating means engaged by said engageable means during a portion of its movement, a contact plate engaged by said engageable means throughout the remaining portion of the movement of said engageable means, a heating element adjacent said

75 75

deflectable member, and a circuit through said contact plate, said engageable member, and said heating element to close the circuit to said heating element when said engageable means is out of contact with said rotatable member.

9. A switch comprising a movable element movable between two extreme positions, a resilient arm secured to said movable element, a bearing plate slidably engageable with said resilient arm including a contact plate and an insulating portion, a cam lug engageable with said arm to flex said resilient arm, said lug holding said arm in contact with said contact plate for a predetermined movement of said movable element in one direction, and out of contact with said contact plate for a predetermined movement of said movable element in the other direction.

10. A switch comprising a reciprocable member movable between two extreme positions, a flexible arm conductive of electricity secured to said reciprocable member, a contact plate upon which

said flexible arm is slidably engaged, said contact plate including a conductive portion and a non-conductive portion and cam means in the path of said arm, said cam holding said arm in engagement with said contact portion flexing said arm until said arm is moved out of engagement with said cam, whereupon said arm flexes quickly onto said non-conductive portion.

11. A switch comprising a reciprocable member, a conductive flexible arm secured to said reciprocable member to move therewith into two extreme positions, a plate slidably engageable with said arm, a conductive and non-conductive portion on said plate, and cam means between said conductive and non-conductive portions, said cam deflecting said arm in one direction as said reciprocable member moves in one direction and flexes said arm in the opposite direction upon the return movement of said reciprocable member.
